UNITED STATES PATENT OFFICE.

HENRIK HILLBOM, OF WALLINGFORD, CONNECTICUT, ASSIGNOR TO THE
R. WALLACE & SONS MANUFACTURING COMPANY, OF SAME PLACE.

DESIGN FOR A BACK FOR BRUSHES, &c.

SPECIFICATION forming part of Design No. 32,209, dated February 13, 1900.

Application filed January 15, 1900. Serial No. 1,571. Term of patent 7 years.

To all whom it may concern:

Be it known that I, HENRIK HILLBOM, of Wallingford, in the county of New Haven and State of Connecticut, have invented and produced a new Design for a Back for Brushes, Mirrors, and Similar Articles; and I do hereby declare the following, when taken in connection with the accompanying drawing and the letters of reference marked thereon, to be a full, clear, and exact description of the same, and which said drawing constitutes part of this specification, and represents a face view of a brush or mirror back embodying my design.

This invention relates to a design for brushes, mirrors, and similar articles; and the design consists in the back, as hereinafter described, and shown in the accompanying illustration.

As herein shown, the back is ornamented by a series of scrolls A, alternated with carnations B. Within some of the scrolls are fully-opened carnations C, while in others buds D are arranged, the essential feature of the design being the combination of scrolls and carnations.

I claim—

The design for a back for brushes, mirrors and similar articles, as herein shown and described.

In testimony whereof I have signed this specification in the presence of two subscribing witnesses.

HENRIK HILLBOM.
